DES 546

Charles Waterman

Design for the Ladies sewing bird.

Patented 15. February 1850

FIG. 1

FIG. 2

Des. 546

Charles Waterman, of Meriden, Conn.
Letters Patent No. 546. Dated Feby 15th 1853.

The schedule referred to in these Letters Patent and making part of the same

To all whom it may concern:

Be it known that I, Chas. Waterman, of Meriden, New Haven, Co. Ct, have invented a new and original design of the instrument known as the "Sewing bird", which design is fully represented by the accompanying drawings.

Fig: 1. is a side elevation of the instrument

Fig: 2. a top view of the same representing a bird on the wing bearing a burden upon its back.

It is a settled principle of taste in all works of Design that the highest degree of beauty is attained where the useful and ornamental are properly blended or combined.

The burden borne upon the back of the bird is in fact the emery ball and while it is an indispensable accompaniment of the sewing bird its position is here appropriate in every respect.

The bird is handsomely feathered and the whole instrument neat and ornamental.

What I claim is the design herein represented by the feathered bird upon the wing, bearing a burden upon its back.
